UNITED STATES PATENT OFFICE.

JEROME ROBINSON BUCHANAN AND ROBERT HARRISON ABBOTT, OF LOS ANGELES,
CALIFORNIA.

DESIGN FOR A BOBECHE FOR ELECTRIC-LIGHT FIXTURES.

Application filed July 3, 1926. Serial No. 18,248. Term of patent 7 years.

To all whom it may concern:

Be it known that we, JEROME R. BUCHANAN and ROBERT H. ABBOTT, citizens of the United States, both residing at Los Angeles, in the county of Los Angeles and State of California, have invented a new, original, and ornamental Design for a Bobeche for Electric-Light Fixtures, of which the following is a specification, reference being had

to the accompanying drawing, forming a part thereof.

Figure 1 is a side view, and Figure 2 is a bottom plan view.

We claim:

The ornamental design for a bobeche for electric light fixtures as shown.

JEROME ROBINSON BUCHANAN.
ROBERT HARRISON ABBOTT.
